COMMUTATOR NOTCHING MACHINE

Lora E. Poole, Anderson, Ind., assignor to General
Motors Corporation, Detroit, Mich., a corpora-
tion of Delaware

Application February 23, 1935, Serial No. 7,755

13 Claims. (Cl. 90—15.1)

This invention relates to sawing devices and more particularly to a device for sawing notches into the segments of a commutator for receiving the leads of armature coils.

It is among the objects of the present invention automatically to index a commutator so as to present consecutive commutator segments to a rotary saw.

It is another object of the present invention automatically to oscillate the rotary saw in alternation with the indexing of the commutator so as to cut notches into consecutive commutator bars.

It is another object of the present invention automatically to stop further indexing of the commutator and oscillation of the saw after all segments of a commutator have been notched.

Further objects and advantages of the present invention will be apparent from the following description, reference being had to the accompanying drawings wherein a preferred embodiment of the present invention is clearly shown.

In the drawings:

Fig. 1 is a perspective view of a device embodying the present invention.

Fig. 2 is a front elevation of the device, certain parts being shown in section, the section being taken on the line 2—2 of Fig. 5.

Fig. 3 is a section taken on the line 3—3 of Fig. 2.

Fig. 4 is an end elevation of the device, certain parts being shown in section, the section being taken substantially on the line 4—4 of Fig. 3.

Fig. 5 is a fragmentary section taken on the line 5—5 of Fig. 2.

Fig. 6 is a section taken on the line 6—6 of Fig. 2.

Fig. 7 is a section taken on the line 7—7 of Fig. 2.

Fig. 8 is a fragmentary section taken on the line 8—8 of Fig. 2.

Fig. 9 is an enlarged section taken on the line 9—9 of Fig. 2.

The present device is adapted to saw a notch into each segment 10 of a commutator 12, the notches being adapted to receive the leads of armature coils after assembly of the commutator with an armature. Generally this device comprises a chuck A for gripping a commutator 12, an intermittently oscillating, rotating saw B for cutting notches into the commutator segments 10, a commutator indexing mechanism C for presenting consecutive commutator segments 10 to the intermittently oscillating saw B, and an

automatic stop D for the device when all segments of the commutator have been notched by the saw.

Chuck A

With particular reference to Figs. 1 and 7, a main frame 20, is mounted in any suitable manner on a work bench or other support 22, is provided with aligned bushings 24 in which a cylindrical member 26 is journaled. Mounted on a reduced portion 28 of member 26 is a disc 30 which is further secured to member 26 by one or more screws 32. Member 26 is held longitudinally immovable in frame 20 by means of a shoulder 34 of said member and disc 30, as can be readily understood. Member 26 is provided with an annular recess 36, receiving the shank 38 of a member 40, secured in said annular recess 36 by means of a set screw 42. Member 40 is centrally recessed as at 44 and has secured therein by means of a set screw 46 a sleeve 48, the upper portion of which is longitudinally split several times so as to provide two or more commutator gripping jaws 50. These jaws are provided with tapered surfaces 52, adapted to cooperate with the tapered end 54 of a bar 56 which passes through sleeve 48 and member 40 and is threadedly received at its lower end by a collar 58 which is slidable in recess 36. Interposed between the shank 38 of member 40 and a washer 60 is a compression spring 62 which normally urges bar 56 in the direction of arrow 64 in Fig. 7, whereby the tapered end 54 of said bar spreads the jaws 50 into clamping engagement with the interior, annular wall 66 of a commutator 12. A rod 68 passes through the cylindrical member 26 and is axially aligned with bar 56. This rod 68 carries at its lower end a plunger 70, cooperating with one end of a foot pedal 72 which is fulcrumed at 74. The gravity of rod 68, plunger 70 and foot pedal 72 urges the same into the position disclosed in Fig. 7 as can be readily understood. If the operator desires to remove a commutator from the chuck A, he merely steps on foot pedal 72, thereby raising rod 68 and bar 56 against the tendency of spring 62 whereby the tapered end 54 of bar 64 is moved out of engagement with the jaws 50 whereupon the latter contract into their natural, unstrained position relative to each other and release the commutator 12 which is then free to be raised from the jaws. Another commutator may then be deposited on the chuck A by bringing the commutator into engagement with a hardened

steel locator 76 which is mounted on sleeve 48. This locator 76 is furthermore provided with a plurality of fingers 78 which are adapted to support the commutator on the segments thereof without, however, interfering with the oscillating saw B while notching segments 10. Also prior to the gripping of a commutator by the jaws 50, i. e. before the operator releases the foot pedal 72, he aligns one of the segments 10 of a commutator with an index finger 80 which extends from a bracket 82, suitably attached to the main frame 20. By thus aligning a segment with the index finger 80, the saw B cuts a notch 10a into another segment 10 of the commutator in the center between two side walls 94 of said segment.

Intermittently oscillating, rotating saw B

With particular reference to Figs. 1 to 4 inclusive, a standard 90 is mounted in any suitable manner on main frame 20 and supports one end of a sleeve 92 which is journaled on a stub shaft 94, one end of which is supported by the main frame 20 as at 96. Mounted on the sleeve 92 is an oscillating frame 98, provided with spaced anti-friction bearings 100 in which a shaft 102 is journaled. This shaft carries at one end a saw 104 and is provided at the other end with an extension 106 which is journaled in an anti-friction bearing 108, provided by the head 110 of a generally tubular frame 112. This head 110 is journaled on the oscillating frame 98 as at 114 and retained thereon by means of nuts 116, threadedly received by the shaft extension 106 and retaining the anti-friction bearing 108 in engagement with a shoulder 118 of said head 110. Frame 112 is furthermore guided for limited rotation about the axis of shaft 102 in a plane at right angles thereto by means of a cage 119 which is secured in any suitable manner to the standard 90 and slidably engaged at two opposite sides by two flat walls 121 of said frame 112. Mounted on shaft 102 intermediate the two bearings 116 is a pulley 120 which is driven by a belt 122, partly covered by a guard 122a and passing below the support 22 as indicated in Fig. 1 and being driven by any suitable power means such as an electric motor (not shown). Although frame 98 is slightly oscillated as will be described presently nevertheless the belt 122 is in constant driving engagement with the pulley 120 since the belt is sufficiently elastic to adapt itself to slight variations in the distance between the driving and driven pulley as caused by the slight oscillation of the frame 98. Pulley 120 is continuously driven, wherefore the saw 104 is continuously rotated.

Referring to Fig. 2, there is shown a shaft 126 which is journaled in anti-friction bearings 128 of the main frame 20 and in a sleeve 130, provided by standard 90. Mounted on shaft 126 is a cam 132, cooperating with an anti-friction roller 134 (see Fig. 3), carried by a bar 136 which is axially adjustably carried by a boss 138 of an arm 140, integral with oscillating frame 98. Pivoted at 142 to the arm 140 is a rod 144 which passes through a stationary lug 146 and is normally urged to the right as viewed in Fig. 3 by means of a compression spring 148, thereby normally tending to rotate the oscillating frame 98 counterclockwise as viewed in Fig. 3.

Commutator indexing mechanism C

With particular reference to Figs. 2, 4, 5 and 7 to 9 inclusive, the disc 30 carries as many equi-

angularly spaced pins 150 as there are segments to a commutator 12. Mounted on shaft 126 is a drum 152, having a peripheral cam groove 154 which comprises a spiral groove portion 156, merging into an angular groove portion 158 which terminates into another spiral groove portion 160, parallel to groove portion 156. In one angular position of the drum 152, the end faces 162 thereof fit between two pins 150a and 150c, while the pin 150b therebetween projects into the annular groove portion 158. Upon rotation of the drum 152 in the direction of arrow 164 in Fig. 9 pin 150a is guided into the spiral groove portion 156 due to the camming action of the spiral groove portion 160 upon pin 150b as can be readily understood. By the time pin 150a reaches the annular groove portion 158, pin 150b has just left the spiral groove portion 160, and when pin 150a leaves the annular groove portion 158 under the camming action of spiral groove portion 160, another pin 150 will have been moved into the spiral groove portion 156. While a pin 150 projects into the annular groove portion 158 of the rotating drum 152, no rotation of disc 30 or of the chuck A takes place as can be readily understood. Rotation of the disc 30 and thereby of chuck A takes place only while a pin 150 cooperates with the spiral groove portion 160. Therefore, the drum 152 may be continuously rotated because only during a certain cycle of one revolution thereof the cam disc 30 is rotated an angular distance equal to that between two consecutive pins 150, whereas during the remaining cycle of one revolution of the drum 152 the saw carrying frame 98 is oscillated so as to cut a notch 10a into one of the segments 10 of the commutator 12.

Shaft 126 is continuously driven by the rotating shaft 102 in a manner to be described presently. Rotatably mounted in the substantially tubular frame 112 (see Figs. 2, 4 and 5) is a shaft 170, one end of which carries a bevel gear 172 which is in constant mesh with another bevel gear 174, mounted on the shaft extension 106. The other end of shaft 170 is provided with a worm 176 (see Fig. 5) which meshes with a worm gear 178, drivingly connected with shaft 126 in a manner to be described later. Projecting from the standard 90 is a stub-shaft 180 on which is journaled a roller 182, adapted to engage a steel wear-plate 184, secured in any suitable manner to the tubular frame 112. A spring urged plunger 186 normally urges the lower end of the tubular frame 112 and more particularly the wear piece 184 thereof into engagement with the roller 182. The roller 182 is so located that upon engagement with the wear plate 184, worm 176 is in proper mesh with worm gear 178. It is evident that during oscillation of the saw carrying frame 98 the tubular frame 112 has slight axial component reciprocations, resulting in reciprocations of the wear plate 184 relative to roller 182 which are, however, so short that the resulting slight bodily movements of worm 176 toward and away from worm gear 178 do not adversely influence the proper cooperation between worm 176 and worm gear 178. In this manner, shaft 126 which carries the indexing cam 152 is continuously rotated by the saw carrying shaft 102 through intermediation of bevel gears 174, 172, shaft 170, worm 176 and worm gear 178. Oscillation of the saw carrying frame 98 result, as already explained, in slight axial component reciprocations of the tubular frame 112. Such reciprocations of frame 112 result in slight longitudinal movements of the worm 176

which are naturally transmitted to the worm gear 178 and alternately slow down and speed up rotation of said worm gear. Due to the very slight oscillation of the saw carrying frame, the 5 continuous change in the rotary speed of the worm gear 178 is so slight that it cannot be noticed and consequently has no adverse influence upon the proper operation of the device.

10 *Automatic stop D*

With particular reference to Figs. 2 and 8, the worm gear 178 is loosely mounted on shaft 126 and provided with clutch teeth 199, adapted to 15 cooperate with corresponding clutch teeth 192 of a clutch member 194 which is splined at 196 to a reduced portion 198 of shaft 126. A portion of shaft 126 is internally recessed at 199 and receives therein a compression spring 200 and a 20 bar 202 which is provided with a transverse pin 204, projecting through two diagonally opposite oblong slots 206 of the reduced shaft portion 198 and secured to the clutch member 194. The 25 compression spring 200 normally urges bar 202 toward the left as viewed in Fig. 2, thereby normally urging clutch member 194 out of engagement with the clutch teeth 192 of worm gear 178. In order to engage clutch member 194 with the clutch teeth 192 of worm gear 178, a manually 30 operable lever 208, pivotally mounted at 210 to cage 119, is manually rocked whereby the same engages bar 202 and shifts the same to the right as viewed in Fig. 2, thereby moving the clutch member 194 into engagement with the clutch teeth 192 of worm gear 178 as can be understood 35 from the foregoing description.

As best shown in Figs. 2 and 7, the disc 30 is provided with an annular rim 212 to which is secured a cam disc 214 having a single depression 216 in its otherwise cylindrical periphery. Co- 40 operating with this cam disc is an anti-friction roller 218, carried by a longitudinally slidable rod 220, floatingly pivoted at 222 to the clutch actuating lever 208. It follows from Fig. 2 that the compression spring 200 normally urges the lever 208 in a counterclockwise direction and the rod 220 to the right, thereby normally retaining the anti-friction roller 218 in engagement with the cam disc 214.

50 It has been earlier explained that the saw carrying shaft 102 is continuously rotated, and that shaft 126 is driven from the saw carrying shaft 102 through intermediation of bevel gears 174, 172, shaft 170, worm 176, worm gear 178 and clutch member 194. While the device is in idle condition, the roller 218 projects into the depression 216 of the cam disc 214 and the clutch member 194 is then cut off engagement with the teeth 192 of worm gear 178. In the idle position of 55 the device, cam 132 assumes the position shown in Fig. 3 in which the saw carrying frame is held in a position in which the saw is most withdrawn from the chuck A as indicated in dot-and-dash lines in Fig. 7, and the indexing cam 152 assumes the position shown in Fig. 9 in which upon renewed rotation of shaft 126, the chuck A is immediately indexed before the saw carrying frame 60 makes its first oscillation. Hence, upon renewed operation of the device the depression 216 of cam disc 214 immediately disaligns from roller 218, permitting the operator to release the clutch actuating lever 208 immediately after manipulation of the same for a re-start of the device. To 65 start the device after a commutator has been 70 removed from the chuck and a new commutator 75

has been deposited thereon, the operator rocks the lever 208 clockwise as viewed in Fig. 2, thereby causing clutch engagement. Since there are as many indexing pins 150 as there are segments 5 10 to a commutator 12, it is obvious that after one complete revolution of the disc 30 all segments of a commutator have been notched by the saw 104. Just after the last segment of a commutator has been notched, the indexing cam continues its rotation until an indexing pin, 10 presently projecting into the annular groove portion 150, assumes the position 150b relative to the rotating cam 152, at which time the depression 216 of said cam re-aligns with the anti-friction roller 218, permitting the same to drop therein under 15 the action of the compression spring 200 so that the lever 208 is rocked into clutch releasing position.

In order to prevent overtravel of the cam shaft 126 after automatic disengagement of clutch 20 member 194 from the clutch teeth of worm gear 178 so as to maintain an initial angular position 25 of the saw oscillating cam 132 and the chuck indexing cam 152, a reduced portion 300 of shaft 126 is provided with a disc 302 the periphery of 30 which is engaged by a suitable brake lining 304 of a brake band 306, adjustably clamped against the disc periphery by nuts 308 which are threadedly received by a bolt 310, projecting from the main bracket 20.

While the embodiment of the present invention as herein disclosed, constitutes a preferred form, it is to be understood that other forms might be adopted, all coming within the scope of the 35 claims which follow.

I claim:

1. In a device of the character described, the combination of a rotatable work-holding chuck; means for indexing the chuck; a swinging frame; a rotatable shaft carried by said frame; a cutter 40 on the shaft; another shaft parallel to the first mentioned shaft and spaced from the axis of rotation of the frame; means on said other shaft for oscillating the frame; and a driving connection between the two shafts, said connection including a third shaft between said two shafts and at right angles thereto, and meshing gears on all shafts.

2. In a device of the character described, the combination of a rotatable work-holding chuck; 50 means for indexing the chuck; a swinging frame; a power rotated shaft carried by said frame; a cutter on the shaft; another shaft parallel to the first mentioned shaft and spaced from the axis of rotation of the frame; means on said other shaft for oscillating the frame; and a driving connection between the two shafts, said connection including a third shaft between said two shafts and at right angles thereto, meshing gears on all shafts and a clutch.

3. In a device of the character described, the combination of a rotatable work-holding chuck; means for indexing the chuck; a swinging frame; a power rotated shaft carried by said frame; a cutter on the shaft; another shaft parallel to the 65 first mentioned shaft and spaced from the axis of rotation of the frame; means on said other shaft for oscillating the frame and for operating the indexing means; and a driving connection between the two shafts, said connection including a third shaft between said two shafts at right angles thereto, meshing gears on all shafts and a clutch.

4. In a device of the character described, the combination of a rotatable work-holding chuck, 75

- means for indexing the chuck; a swinging frame; a power rotated shaft carried by said frame; a cutter on the shaft; another shaft parallel to the first mentioned shaft and spaced from the 5 axis of rotation of the frame; means on said other shaft for oscillating the frame and for operating the indexing means; a driving connection between the two shafts, said connection including a third shaft between said two shafts 10 and at right angles thereto, meshing gears on all shafts and a manually connectible clutch; and means disconnecting the clutch in response to a preassigned number of indexing steps of the chuck.
- 15 5. In a device of the character described, the combination of a rotatable work-holding chuck; a swinging frame; a rotatable shaft carried by said frame; a cutter on the shaft; another shaft spaced from the axis of rotation of the frame; 20 means on said other shaft for oscillating the frame; a tubular member supported at one end by the frame for rotation in a plane at right angles to said other shaft, the other end of said member being guided for movement in said 25 plane; a driving connection between both shafts, said connection including a shaft in the member and carrying a worm, and a worm gear on said other shaft; an anti-friction roller the axis of which is located in a plane which is rectangular to the shaft in the member and in which the 30 axis of the worm gear lies; and a spring urged plunger urging the member away from the worm gear and into engagement with the roller in which position the worm is in proper mesh with 35 the worm gear.
6. In a device of the character described, the combination of a rotatable chuck for holding a commutator; an oscillatable and power rotated tool for cutting notches into the segments of the 40 commutator; means for indexing the chuck to present consecutive commutator segments to the tool; rotary means for operating the indexing means; a driving connection between the power rotated tool and said rotary means, said connection including a clutch; means for automatically disengaging the clutch after all segments of the commutator have been notched; and means 45 permanently frictionally braking rotation of said rotary means.
- 50 7. In a device of the character described, the combination of a rotatable disc; equi-angularly spaced projections carried by the disc, and a rotatable cam adapted to cooperate with consecutive 55 projections in order to index the disc.
- 55 8. In a device of the character described, the combination of a rotatable disc; equi-angularly spaced pins projecting from the disc; and a rotatable drum having a peripheral cam groove adapted to cooperate with consecutive pins in 60 order to index the disc.
- 65 9. In a device of the character described the combination of a rotatable disc; equi-angularly spaced pins projecting from the disc; and a rotatable drum having a peripheral cam groove adapted to cooperate with consecutive pins, said

cam groove being so designed that during a pre-assigned cycle of one revolution of the drum the disc is indexed and during the remaining cycle of said one revolution the disc remains stationary.

10. In a device of the character described, the combination of a rotatable disc; equi-angularly spaced pins projecting from the disc; and a rotatable drum having a peripheral cam groove adapted to cooperate with consecutive pins, said cam groove being composed of a spiral groove portion merging into another groove portion lying in a plane at right angles to the drum axis and a second spiral groove portion parallel to the first said spiral groove portion and merging from said other groove portion, the distance between the two spiral groove portions and their coordination being such that two consecutive pins may be simultaneously received therein and moved thereby upon rotation of the drum.

11. In a device of the character described, the combination of a rotatable disc; equi-angularly spaced pins projecting from the disc; and a rotatable drum having a peripheral cam groove adapted to cooperate with consecutive pins, said cam groove being composed of two opposite parallel spiral groove portions joined midway between the entrances to both groove portions by another groove portion lying in a plane at right angles to the drum axis, the entrances to the spiral groove portions being aligned in the direction of the drum axis and spaced apart a distance substantially equal to the clearance between two pins which are consecutive to a third pin therebetween.

12. In a device of the character described, the combination of a rotatable work-holding chuck; means for indexing the chuck; an oscillatable and power rotated tool for notching the work; rotary means for operating the indexing means and for oscillating the tool; a driving connection between the tool and the rotary means, said connection including a normally disengaged clutch; a manually operable clutch engaging arm; and means including a cam carried by the chuck for retaining said arm in clutch engaging position for one revolution of the chuck.

13. In a device of the character described, the combination of a rotatable work-holding chuck; means for indexing the chuck; an oscillatable and power rotated tool for notching the work; rotary means for operating the indexing means and for oscillating the tool; a driving connection between the tool and the rotary means, said connection including a normally disengaged clutch; a manually operable clutch engaging arm; a cam disc having a single depression in its otherwise concentric periphery and being carried by the chuck; and a link cooperating with the cam periphery and connected to the arm for retaining the latter in clutch engaging position while cooperating with the concentric portion of the cam periphery, and controlling clutch disengagement when cooperating with the cam depression.
